UNITED STATES PATENT OFFICE.

FRANCIS M. OGLE, OF CHEYENNE, OKLAHOMA, ASSIGNOR OF ONE-THIRD TO CHARLES P. MCCLAIN AND MORRIS L. EBSTONE, BOTH OF CHEYENNE, OKLAHOMA.

FOLDING POULTRY-COOP.

1,267,585.

Specification of Letters Patent.

Patented May 28, 1918.

Application filed July 7, 1917. Serial No. 179,211.

To all whom it may concern:

Be it known that I, FRANCIS M. OGLE, a citizen of the United States, residing at Cheyenne, in the county of Roger Mills and State of Oklahoma, have invented a new and useful Folding Poultry-Coop, of which the following is a specification.

The device forming the subject matter of this application is a coop, and one object of 10 the invention is to provide a coop which may be folded into small space, to facilitate shipment.

Another object of the invention is to provide novel means for holding the top of the 15 coop in place, both when the coop is set up and when the coop is knocked down for shipment.

Another object of the invention is to provide novel means whereby the ends of the 20 coop are interengaged with the sides, to prevent the ends and the sides from swinging outwardly to an undesirable extent, when the coop is set up.

A further object of the invention is to improve generally and to enhance the utility 25 of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the 35 invention herein disclosed can be made within the scope of what is claimed, without departing from the spirit of the invention.

In the accompanying drawings:

Figure 1 shows in side elevation, a coop 40 constructed in accordance with the present invention;

Fig. 2 is a top plan of the coop;

Fig. 3 is a sectional detail showing the 45 latch mechanism whereby the top of the coop is held in place;

Fig. 4 is a longitudinal section of the coop;

Fig. 5 is a side elevation of the coop, the 50 same being collapsed for shipment, parts being broken away;

Fig. 6 is a transverse section taken through one side wall of the coop and the top thereof;

Fig. 7 is a composite perspective view

showing a portion of one side and a portion 55 of one end of the coop, the view being introduced for the purpose of delineating the elements which, being located on the parts above specified, limit the outward swinging movement of the sides and the ends of the 60 coop.

The coop forming the subject matter of this application may be made of any desired material such as wood and includes a base, comprising a bottom 1. Spacing members in the form of reinforcing cleats 2, extend transversely of the bottom 1 and are secured thereto. Side bars 3 are superposed on the bottom 1 and upstand therefrom, the side bars being secured to the bottom. Side 70 frames 4 are located above the bars 3 in alinement therewith. The side frames 4 are connected with the side bars 3 by means of hinges 5, so that the side frames may be folded inwardly. The side frames 4 may be 75 closed in by wire screens 25 or otherwise. On their inner sides, at their ends, and intermediate their ends, the side frames 4 are supplied, near their upper edges, with recesses 6. Keeper plates 7 are secured to the 80 side frames 4 and bridge the recesses 6. The keeper plates 7 are supplied with curved slots 8 having mouths 9 which open through the lower edges of the plates.

End frames 10 are disposed between the 85 side bars 3. The end frames 10 are closed in by screens 26. Pivot elements 11 pass through the side bars 3 and support the end frames 10, so that they can be swung inwardly. An intermediate frame 14 is disposed between the side bars 3. The intermediate frame 14 may be closed in by a screen 28. Pivot pins 15 pass through the side bars 3 and engage the intermediate frame, so that the intermediate frame may 95 be folded down parallel to the bottom 1. The intermediate frame 14 includes a top bar 27 and a bottom bar 29. The construction is such that the end frames 10 may be folded down flat on the bottom 1, between the side 100 bars 3, it being possible to fold the intermediate frame 14 downwardly on the bottom also. When the end frames 10 and the intermediate frame 14 are folded down flat on the bottom 1, the side frames 4 may be 105 folded toward each other so as to rest on top of the end frames 10 and the intermediate frame 14, the side bars 3 serving to elevate

the side frames 4 sufficiently so that this result may be brought about. The side frames 4 may be swung upwardly until they stand at right angles to the bottom 1, and 5 the end frames 10 may be swung upwardly until they stand at right angles to the bottom 1. When the end frames 10 are swung upwardly as above described, headed projections 12 on the extremities of the end 10 frames 10 pass into the slots 8 of the keeper plates 7 on the side frames 4, and the heads of the projections 12 engage behind the plate. In this way, the side frames 4 are prevented from swinging outwardly to an 15 undesirable extent, and, at the same time, the end frames 10 are prevented from swinging outwardly in opposite directions beyond a predetermined point. The intermediate frame 14 is interengaged in a similar 20 way with the side frames 4.

Supported on the end frames 10 and on the side frames 4 is a top frame 16 including an intermediate bar 51. The top frame 16 is provided at its corners with metal sockets, 25 which receive the edges defined by the side frames 4 and the end frames 10, when the coop is set up, as shown in Fig. 1. The sockets 50 also coat with the side frames 4 and the end frames 10 when these frames 30 are folded inwardly over the bottom 1, the parts being shown thus arranged in Fig. 5. The top frame 16 may embody a screen 25'. An opening 28 is fashioned in the screen 25', and the opening extends on both sides 35 of the intermediate bar 51. Pivot rods 52 are held upon the bar 51 by means of eyes 30. Wire closures 31 are connected with the pivot rods 52. The closures 31 swing upwardly against the under side of the 40 screen 25' to close the opening 28. Helical springs 53 are engaged around the pivot rods 52. The springs 53 terminate in oppositely extended resilient arms 34 engaged beneath the closures 31, and tending to 45 swing the same upwardly to closed positions. It is possible to place a hen in the coop by pressing the closures 31 inwardly, whereby upon the closures will swing upwardly under the action of the spring arms 34, into 50 closed positions.

The top bar 27 of the intermediate frame 14 carries a headed pin or bolt 35 which extends vertically when the intermediate frame 14 is vertically disposed. The bottom 55 bar 29 of the intermediate frame 14 has a laterally extended projection 36 which is shown in Fig. 4. There is an opening 37 in the intermediate bar 51 of the top frame 16. When the coop is set up, the headed pin 60 35 extends through the opening 37. A latch 38 is mounted to slide endwise on the intermediate bar 51 of the top frame 16. The latch 38 is provided at one end with a notch 39 adapted to engage the pin 35, beneath 65 its head, when the latch 38 is advanced.

The latch 38 has a longitudinal slot 40. A headed securing element 41 passes through the slot 40 and engages the intermediate bar 51 of the top frame 16. The securing element 41 serves to hold the latch 38 upon 70 the intermediate bar 51. The latch 38 is provided at one end with an upstanding finger piece 42 whereby the latch may be slid endwise. In the intermediate bar 51 there is formed a recess 43. A spring strip 75 or keeper 44 operates in the recess 43 and is attached at one end to the intermediate bar 51. At its other end, the spring strip 44 has a head 45 operating in the slot 40 of the latch 38.

When the parts are arranged as shown in Fig. 3, the forked or notched end 39 of the latch 38 is engaged beneath the head of the pin or bolt 35 and, consequently, the top frame 16 is held in place on the body portion of the coop, as indicated in Fig. 1. The head 45 on the spring strip 44 contacts with the latch 38 at one end of the slot 40, and consequently the forked end 39 of the latch 38 can not be disengaged accidentally 90 from beneath the head on the pin or bolt 35. Through a forcible pull exerted on the latch 38 by means of the finger piece 42, the latch 38 may be retracted, the spring strip 44 retiring into the recess 43.

Let it be supposed, however, that the coop is in the folded condition shown in Fig. 5. Then the headed projection 36 carried by the bottom bar 29 of the intermediate frame 14 extends upwardly through the 100 opening 37 in the intermediate bar 51 of the top 16, and the latch 38 can be engaged with the headed projection 36, after the manner of Fig. 3, to hold the top frame 16 in place when the coop is folded.

The device forming the subject matter of this application is simple and embodies few parts, and the construction is such that the coop may be set up or knocked down without difficulty, and when the coop is 110 knocked down, as shown in Fig. 5, it will occupy but little space.

Having thus described the invention, what is claimed is:—

A coop comprising a base; an upstanding wall hinged to the base and adapted to be folded on the base; a top disposed above the base when the wall upstands and when the wall is folded, the top having an opening; projections on the wall and disposed at an angle to each other, one of said projections extending through the opening when the wall upstands, the other of said projections extending through the opening when the wall is folded; a latch slidably mounted on the top and co-operating with the projections at different times, the latch having a longitudinal slot; a securing element extended into the slot and connected with the top, the securing element holding 130

the latch on the top for sliding movement; and a spring keeper mounted on the securing element, beneath the latch, one end of the spring keeper coacting with the latch 5 at one end of the slot, to hold the latch advanced with respect to the projections, the top having a recess into which the spring keeper is adapted to retire.

In testimony that I claim the foregoing as my own, I have hereto affixed my signature in the presence of two witnesses.

FRANCIS M. OGLE.
